CARPET SWEEPER

Joseph Stern, Newark, N. J., assignor to Sweeper Products Co., Newark, N. J., a corporation of New Jersey

Application January 27, 1937, Serial No. 122,487

2 Claims. (Cl. 15—48)

This invention relates to improvements in carpet sweepers and more particularly to improvements in carpet sweepers having a dust-pan removable through the top thereof.

5 An object of the present invention is to provide new, simple and efficient mechanism for cleaning lint and the like from the brush roll of a carpet sweeper.

Another object of the invention is to provide a brush roll cleaning device which can be readily attached to and removed from a carpet sweeper.

A still further object of the invention is to provide a brush roll cleaning mechanism which is readily detachable to and removable from an open 15 top dust-pan which dust-pan itself is capable of being readily removed from and introduced into a carpet sweeper casing through the open top thereof.

In carrying out the foregoing and other objects 20 of the invention, the carpet sweeper incorporating the invention comprises a frame or casing so constructed as to have a substantially complete open top adapted to be closed by a cover hinged thereto. Secured to the frame are supporting 25 and driving wheels, and also secured to the frame are brush supporting plates so mounted as to be capable of limited vertical movement. The brush supporting plates also serve as supports for an open top dust-pan which can be introduced into 30 the frame and removed therefrom through the open top of the frame. By this arrangement, the dust-pan is mounted for vertical movement simultaneously with the brush roll.

Since the bristles of a brush roll during use 35 are prone to collect lint, threads, and other matter which cannot be dislodged therefrom during the normal operation of the brush, the present invention provides means for removing or 40 combing such lint, threads, etc. from the brush roll during operation. A comb for this purpose is preferably made of metal or some other unyielding material, and such comb necessarily will impose undue wear on the bristles of the brush if 45 permitted to contact therewith at all times. Accordingly, the comb is mounted for ready attachment to and detachment from a part of the carpet sweeper. To facilitate such attachment and detachment, means are provided for receiving and holding the comb between parts of the dust-pan so that the comb can be removed from the casing along with the pan and can be removed 50 from the pan either while the pan is in the casing or when the pan has been separated from the casing.

55 Other features, objects and advantages of the

invention will become apparent by reference to the following detailed description of the accompanying drawings wherein:

Fig. 1 is a plan view of a device embodying the invention with the cover in open position; 5

Fig. 2 is a section taken substantially on the line 2—2 of Fig. 1;

Fig. 3 is a section taken substantially on the line 3—3 of Fig. 1;

Fig. 4 is an enlarged perspective view of a dust-pan having comb receiving sockets in the opposite ends thereof; 10

Fig. 5 is a fragmentary side elevation of a comb utilized in the invention;

Fig. 6 is an end view thereof; and 15

Fig. 7 is a fragmentary showing of the construction of one end of each carrier plate illustrating the manner in which the dust-pan is supported thereby for movement therewith.

Referring now to the drawings, 10 indicates 20 generally a casing or frame made up of side plates 11 and end plates 12 secured thereto. The side plates may be of any suitable material such as wood, metal, etc., but the end plates preferably are made of metal so shaped and secured to the 25 side plates 11 as to provide rounded corners. The casing or frame so made up of these plates is entirely open at the top and a cover 14 hingedly secured to one side thereof serves to close the 30 opening in the top of the casing. 30

Carrier plates 15 are secured within the casing adjacent each end plate 12. These plates are secured to the casing by studs 16 which extend through slots 17 in the respective end plates 12 and which have brush roll bearing portions 18 35 adjacent the inner faces of the carrier plates. The usual bail 19 is secured to the studs 16 for actuating the sweeper and for controlling vertical movement of the carrier plates within the limits defined by the length of the slots 17. Each 40 carrier plate 15 is held normally in uppermost position by a spring 20 secured to an end plate 12 intermediate the ends of the spring as shown at 21, and secured to the carrier plate at each end of the spring as indicated at 22. Fingers 24 45 pressed from the carrier plate serve to hold each carrier plate in proper spaced relation from its associated end plate.

The supporting and driving wheels 30 are independently rotatably mounted on plates 31 50 which in turn are pivotally secured to the end plates 12. Spacer members 32 serve to position the respective plates 31 inwardly of the carrier plates 15. The free ends of the plates 31 are provided with legs 34 which in cooperation with 55

fingers 35 punched from the end plates serve to limit pivotal movement of the plates 31 about their axes. By this arrangement it follows that the respective supporting and driving wheels 30 5 are mounted for rotation and also for limited arcuate movement about the axes of the pivotal connections between plates 31 and end plates 12. The carrier plates 15 are cut away to accommodate the pivotal mounting of the wheel plates 31 10 and also to accommodate the stop fingers 35 without interfering with vertical movement of the carrier plates.

A bristle roll 40 has pins 41 at the ends thereof for bearing contact with the bearing members 15 18. The brush roll is so constructed that the pins 41 can be disengaged from the sockets 18 to permit removal of the brush through the top of the frame or casing. The brush roll 40 is also provided with integral pulley members 42 positioned 20 to be engaged by the supporting and driving wheels 30. Inasmuch as the brush is mounted for limited vertical movement along with the carrier plates 15, the provision of the arrangement whereby the supporting wheels are capable 25 of limited arcuate movement makes possible a good frictional contact between the driving wheels and the pulleys 42 in all positions of the brush roll.

The ends of the carrier plates 15 are bent 30 around, as indicated at 45, and upstanding fingers 46 extend upwardly from the normal top edge of the carrier plate. These fingers are bowed intermediate their length as indicated for a purpose to be explained later. In addition to the 35 fingers 46, the extensions 45 of the carrier plates are also provided with fingers 47 adjacent to but extending at an angle from the fingers 46. The purpose of these fingers will also be explained later.

40 The dust-pan indicated generally at 50 is constructed preferably of metal into the shape shown clearly in Fig. 4, wherein two dust receiving compartments 51 are provided, such compartments being adapted to be located at the opposite sides 45 of the bristle roll 40. This arrangement is shown clearly in Fig. 3. The side walls 52 of the dust-pan are provided with turned over edges 54 spaced a slight distance from the side wheels 52. These turned over edges 54 are adapted to engage the 50 outer surfaces of the fingers 46 with the upper ends of the fingers introduced into the space between the parts 52 and 54. The bowed portions of fingers 46 serve to provide a good frictional contact between the fingers and the dust-pan 55 to hold the dust-pan sufficiently secure to the extensions of the carrier plate as to insure movement of the dust-pan simultaneously with the carrier plates and also with the brush roll. The fingers 47 serve to determine positioning of the 60 dust-pan in proper assembly since these fingers extend in close relation to the end plates of the dust-pan. A handle 55 extends between the end plates of the dust-pan to facilitate handling thereof.

65 Two socket members 56 are secured in any suitable fashion to the opposite end plates of the dust-pan, such sockets being disposed at an angle to the vertical and being provided with open

tops, closed bottoms, and open sides, such open sides being directed inwardly of the pan. These sockets are provided to receive a comb indicated generally at 60. The comb comprises a back 61 made preferably, but not necessarily, of some 5 suitable metal, such back being provided with a longitudinal bead 62. Extending from one edge of the back 61 are a plurality of teeth 64 formed integral with the back. The bead 62 is of such dimensions as to cause the back 61 to fit snugly 10 in the sockets 56 with a sufficient amount of friction as to insure the comb being retained in the sockets against adventitious removal. However, the fit is not tight enough to interfere with ready 15 removal of the comb from the sockets.

In use of the present invention, the comb 60 can be engaged in the sockets 56 at any desired time, such use of the comb being ordinarily made only when the bristles of the roll 40 have collected an undesirable amount of lint, threads and the 20 like. When so in place, the comb serves to remove such lint, etc., from the brush, and when this purpose has been achieved, the comb can be readily removed from the assembly since continued use thereof might possibly shorten the 25 life of the bristles.

Since the comb is removably secured to the dust-pan, and since the dust-pan is readily removable from the casing, it follows that the comb can be removed either from the dust-pan while 30 the pan is in the casing, or from the dust-pan while the pan is detached from the casing. Thus, it follows that the use of the comb is facilitated.

From the foregoing it will be seen that the invention provides novel, efficient and simple 35 means for quickly cleaning the bristles of a carpet sweeper bristle roll, which cleaning means can be used intermittently as desired, thereby causing no harmful effects on the bristles of the bristle roll.

It is to be understood that the invention is 40 capable of modification; in view of which any limitations imposed thereupon are to be such only as are set forth in the following claims.

What is claimed is:

1. A sweeper of the type described comprising a casing having an open top, a driven bristle roll mounted therein, an open top dust-pan removably mounted in said casing adjacent to said bristle roll, socket means secured to the inner 50 sidewalls of said pan, and a comb removably engaged in said sockets, said comb having a back provided with a longitudinal bead for providing frictional contact of the back with the sockets and having teeth adapted to be located in the 55 path of movement of the bristles of said roll.

2. As an accessory for a sweeper of the type described, an open top dust-pan, socket members secured to the inner sidewalls of said pan, said socket members having closed bottoms, open tops, and open sides facing each other, and a comb for engagement in said sockets, said comb comprising a strip-like back provided with a longitudinal bead for frictional engagement in said sockets and having integral teeth extending from 65 one edge of said back.

JOSEPH STERN.
